[57] CLAIM

The ornamental design for a surgeon's hood, as shown and described.

DESCRIPTION

FIG. 1 is a front perspective view of a surgeon's hood showing our new design;

FIG. 2 is a top plan view thereof;

FIG. 3 is a front elevational view thereof;

FIG. 4 is a right side elevational view thereof wherein the left side elevational view is a mirror image thereof;

FIG. 5 is a rear elevational view thereof; and,

FIG. 6 is a bottom plan view thereof.

The broken lines in FIGS. 1-4 and 6 represent conventional stitching.

FIG-1

FIG-2

FIG-3

FIG-4
